ADJUSTING APPARATUS IN EDGING MACHINES

Kaleb Emil Evrell, Eskilstuna, Sweden, assignor to Aktiebolaget Bolinder-Munktell, Eskilstuna, Sweden, a corporation of Sweden

Application February 19, 1937, Serial No. 126,730
In Sweden March 17, 1936

3 Claims. (Cl. 121—41)

The edging machine in a sawing plant has for its object to trim the rough edges of the wood obtained from the saw frames. The board or plank is advanced by feed rollers towards two edging blades which are set in a desired distance from each other. For each plank reaching the edging machine the edging operator has to judge the width which may be obtained therefrom, set the movable saw-blade in a corresponding position and lock it therein, and push the plank into a position so as to be gripped by the feed rollers. Since the width of the wood varies to a great extent, and usually, it is important to obtain a maximum of width of each plank, practically each 10 plank passing the edging machine requires its particular width adjustment. It is true that in a present-day easily operable edging machine each adjusting operation requires a rather small amount of work but with the more and more forced working speed which is now used the physical effort will be very considerable. The shifting operations must in fact be performed in a quick succession and rapidly as possible.

However, considerable difficulties have been met with in rendering the adjustment of the work or saws automatic due to the preciseness required to keep the dimensions of the wood within the narrow limits which are required from a point of view of quality. When sawing the wood 20 it is often rough, often taken directly from the water, and must then be sawed to surplus dimensions gauged so that the sawed wood after drying still comes up to the standard in spite of the reductions of dimension accompanying the drying. The magnitude of said drying shrinking has been gathered from practice; generally, in northern sawing plants the wood is edged to dimensions about $B=1.013 \times B_0 + 2$ mm., where B_0 is the nominal width. Thus, for a nominal width of 7 30 inches $B=1.013 \cdot 7 \cdot 25.4 + 2 = 182.1$ mm. according to said formula instead of the nominal gauge 177.8 mm. As a rule, conventional edging machines are provided with a locking rod comprising stop notches spaced $1.013 \cdot 25.4 = 25.7$ mm. apart 40 from each other corresponding to 1" of nominal change of dimension. An adjustment of half inches is also used for smaller widths. By an axial adjustment of said rod it is possible to adjust to various additions of dimension but no change 50 of the magnitude of the displacement, i. e. the distance between the stop notches is possible.

The present invention has for its object to facilitate the work of shifting the saw-blades. In the first place, this is obtained according to the invention by an apparatus which is adapted

to set the saw-blades in position by means of an auxiliary power, preferably by a pressure medium for the generation of the auxiliary power. According to a feature of the invention the apparatus is constructed so as to shut off the auxiliary power when the saw-blades have moved to the desired extent, and according to a further feature this shutting-off is effected by the adjusting movement of the saw-blades. The edging operator has only to set an easily movable operating member in a position which corresponds to the desired dimension of width, whereupon the adjusting apparatus driven by auxiliary power effects the displacement of the saw-blades and the interruption of the adjusting movement automatically, and keeps the saw-blades in the adjusted position. In the embodiments of the invention described below an operating slide is set in position directly or indirectly by the operator but the remaining work for the adjustment of the saw-blades is effected automatically. The movements of the operating slide correspond to definite adjusting movements of the saw-blades. The operating slide is completely balanced and thus easily displaceable so as to be easily set in 5 position. The pressure medium delivering the auxiliary power acts, according to a further feature of the invention, upon one or more pistons which are connected with the saw-blades or a working table carrying said blades in such a 10 manner that the connecting or transmitting elements are always exposed to constant forces in one direction. By this means any influence of play and resiliency in said transmitting elements will be eliminated and the preciseness of the 15 adjustment will only become dependent upon the exactness with which an index division determining the adjustment positions of the operating 20 slide is constructed.

The application of the invention is shown by 25 way of example in the accompanying drawings.

The construction will be cleared more in detail by the accompanying drawings.

Fig. 1 is a side elevation of an edging machine 30 having a hydraulic adjusting apparatus according to the invention.

Fig. 2 is a sectional view along the driving shaft 35 thereof and a transverse view of the adjusting mechanism.

Figure 3 is a view of one end of the apparatus 40 showing parts in section for the purpose of clearness of illustration.

Figure 4 is a vertical sectional view taken substantially along the line 4—4 of Figure 3 and,

Figure 5 is a sectional view taken substantially along the line 5—5 of Figure 3.

Both saw-blades 1 and 2 are driven by a belt on the pulley 3. The blades are fixed on tubular shafts 4 and 5 respectively the former of which is journalled in the table 7 displaceable on guides 6, and the latter in the fixed frame. As usual, the driving power for the displaceable blade 1 is transmitted by a spline shaft 8 axially displaceable in the tubular shaft 5. 9 designates feed rollers of a usual type.

The shifting shaft 10 carried in the frame is connected with the table 7 by levers 11 and links 12. Keyed to said shaft is a lever 13 having, at the outer end thereof, an adjusting screw 14 forming a stop for the lever which comprises two plates 15 and is provided with an eccentric pin 16 (Fig. 3).

The operating liquid works in two cylinders including a main cylinder 17 and an auxiliary cylinder 18 the former of which constitutes a housing for a slide valve and its associated parts. The auxiliary cylinder 18 provides a pressure cylinder in which the piston or the plunger 19 works. The plunger 19 is fixed to the working table 7 and is of larger effective area than the piston 24.

The pressure oil is supplied to the main cylinder 17 through the passage 20. The main cylinder communicates with the pressure cylinder 18 by the channel 21 and the tube 22. The pressure oil is delivered from an oil pump of a conventional type not shown. The cylinder 17 encloses a double slide arrangement consisting of an outer slide or piston 24 and an operating slide valve 25 disposed in side thereof. The pressure oil 30 enters the chamber 28 below the operating slide through bores 26 and 27 (Figs. 3 and 4). Said chamber as well as the cylinder chamber 29 above the piston 24 has thus a pressure above the atmospheric. Two portions of the piston 24 are cut away to form grooves 30 and 31 the former of which communicates constantly with the pressure cylinder 18 by the passage 21 and the tube 22, and the latter communicates constantly with the return conduit or exhaust by the passage 23. The grooves 30 and 31 communicate with the inner bore of the piston 24 by ports 32 and 33. The annular groove or reduced portion 34 which is constantly pressure-free due to the connection with the return conduit over the groove 31 and the passage 23 serves to release the packing 35 from any oil pressure. Also the packing 36 for the plunger 19 is released in a similar manner from the oil pressure by the cutting-out 37 which communicates with the return conduit by a tube. The oil pressure acts constantly on the outer slide 24 by a force

$$\frac{\pi D^2}{4}$$

60

wherein p is the oil pressure per unit of area and D the inner diameter of the slide housing. Said force is transmitted to the table 7 by the link 38, pin 16, shaft 10, levers 11 and links 12. In order to obtain uniform movements of the table 7 and the outer slide 24 the lengths of the links 12 and 38 are made proportional to the lengths L and l of the levers and further the positions of the pins are made such that in each position of the table 7 the angle between the centre lines of the link 12 and the lever 11 is approximately equal to the corresponding angle of the link 38 and lever 15.

The force which tends to carry the table 7

and the blade 1 from the left to the right (Figs. 2 and 3) is

$$P = p_1 \frac{\pi d^2}{4} - p \frac{\pi D^2 l}{4 L}$$

wherein p_1 is the pressure above atmospheric of the oil in the pressure cylinder 18 and p is the pressure above atmospheric of the oil in the slide housing 17. p is equal to the available work pressure, p_1 being able to vary between p and 0 as will be shown in the following.

As shown in Fig. 3, d and D are the diameters of the pistons 19 and 24 respectively, and l and L are the effective lengths of the levers 15 and 11 respectively.

$$P_{max} = p \frac{\pi d^2}{4} - p \frac{\pi D^2 l}{4 L}; P_{min} = 0 \frac{\pi d^2}{4} - p \frac{\pi D^2 l}{4 L}$$

P_{min} is apparently negative, that is a force of the magnitude

$$p \frac{\pi D^2 l}{4 L}$$

which is directed from the right to the left.

Should an access to the same power for the movement of the table 7 in both directions be desired the diameters and lever lengths should be designed so that $P_{max} = -P_{min}$, that is

$$p \frac{\pi d^2}{4} - p \frac{\pi D^2 l}{4 L} = p \frac{\pi D^2 l}{4 L}$$

which gives:

$$\frac{d^2}{D^2} = \frac{2l}{L}$$

The diameters and leverage are chosen so as to approximately satisfy said formula. The condition that P is equal to naught, that is that the forces acting on the table 7 would balance each other is obtained from the formula:

$$0 = p_1 \frac{\pi d^2}{4} - p \frac{\pi D^2 l}{4 L}$$

and gives:

$$p_1 = \frac{D^2 l}{d^2 L} p$$

or if

$$\frac{D^2}{d^2} = \frac{L}{2l}$$

be inserted: $p_1 = \frac{1}{2} p$.

The shifting movements will be obtained by varying the pressure in the cylinder 18 in an adequate manner.

The operating slide value 25 is displaced by means of the handle 39 on the double lever 40 from which the movement is transmitted by the rod 41, lever 42, shaft 43 and toothed segment 44 to the extension 45 of the operating slide 25 constructed as a toothed rack, Figs. 1 and 3.

The toothed rack 45 has also a series of grooves or index 47 in which the spring-loaded pawl 46 may engage. All surfaces of the operating slide value 25 and its extension 45 except those which are adjacent to the annular chamber 48 are always exposed to the pressure p . Thus the oil pressure cannot displace said slide but it is completely balanced. Should the handle 39 be displaced from the position shown in Fig. 1 so as to move the slide value 25 to an extent δ so as to reach the next groove for the pawl, communication is established between the chambers 28 and 30 by the fact that the lower part 49 of the operating slide 25 uncovers the passage 32 in the piston 24. The pressure oil from the chamber 70 is now free to flow to the pressure cylinder 18 through the holes 26 and 27, passage 32, chamber 30 and tube 22. Consequently, the pressure p_1 in said pressure cylinder may arise to p . As stated above, the table 7 will now move to the

75

right (the space between the blades 1 and 2 decreases). Due to the connection of the table 7 and the piston 24 over the shaft 10, the piston is compelled to be pushed upwards by said movement. When the piston has now moved to an extent δ , that is to the same extent as the operating slide had been displaced, the passage 32 will be covered again by the portion 49 of the operating slide. The axial length of the portion 49 is made slightly (0.1 to 0.2 mm.) smaller than the axial dimension of the passage 32. Consequently, said passage is never closed completely by the portion 49 of the operating slide but the whole arrangement will act as a strong restriction of the connection from the chamber 28 over the port 32 to the chamber 48. The operating pressure p exists in the chamber 28, and in the chamber 39 the same pressure is present as in the working cylinder 18 with which it communicates, that is a pressure which was previously designated by p_1 , whereas no pressure above atmospheric exists in the chamber 48 which communicates constantly with the outlet conduit 23 by the passage 33. As shown above the forces from the piston 24 and the piston 19 balance each other when $p_1 = \frac{1}{2} p$. Equilibrium will thus occur when the portion 49 has been adjusted to such a position in relation to the port 32 that the pressure drop from the chamber 28 to the passage 32 is equal to the pressure drop from the same passage to the chamber 48.

The piston 24 has moved to exactly the same extent δ as the operating slide valve 25 when the forces balance each other. This movement corresponds to a movement of the table of

$$\delta \times \frac{L}{l}$$

and the space δ between the index grooves 47 is to be chosen with regard to the ratio

$$\frac{L}{l}$$

so that correct intervals of displacement are obtained.

Should the slide valve be displaced downwards instead of upwards, the slide portion 49 will uncover the port 32 so as to establish a communication between the pressure cylinder 18 and outlet 23. The pressure p_1 then becomes naught and the table 7 moves to the left. After such movement of the operating slide valve 25 the piston 24 will move downwards and equilibrium occurs as before when the piston has moved to such an extent as to have the centre of the passage 32 in register with the centre of the portion 49 of the operating slide, that is also in this case after a movement exactly as great as the displacement of the operating slide valve.

The above-mentioned handle lever 40 with the handle 39 has a pointer 50 fixed on the lever 40. Said pointer moves along a graduated scale 51 which is graduated in the nominal widths for which the edging machine is adapted. The scale 51 is only adapted for an approximate adjustment whereas the fine adjustment is effected automatically by the pawl 46 as soon as the handle lever has carried the slide 25 in the proximity of the desired position.

As hereinbefore shown the intervals of displacement of the table 7 are

$$\delta \times \frac{L}{l}$$

δ and L are constant measures whereas the lever lengths l may be changed by turning the eccentric

bolt 16. By screwing the adjusting screw 14 when the oil pressure in the system holds the piston 24 in a certain fixed position of the operating slide valve 25 the table 7 is displaced without changing the operating slide. The before-mentioned formula $B = 1.013 B_0 + 2$ for widths to which the raw wood is edged may also be written $B = B_0 + m B_0 - n$, wherein B is the desired width of wood with added drying measure, B_0 nominal width of wood and m and n constant quantities. The constant quantity m is changed by turning the eccentric bolt 16, that is the percentage of surplus is varied thereby, and by adjusting the adjustment screw 14 the constant quantity n is varied, which is the same as an amendment of the constant addition to the width. These both adjustment possibilities serve to eliminate faults of construction in the edging machine itself and give at the same time convenient possibility for each individual edging machine owner to set the surplus on values which suit for his type of wood.

It will be seen that the piston 24 is acted upon at all times by the pressure liquid or medium in the chamber 29. Due to the connection of the piston 24 with the table 7 through the lever mechanism, the force exerted by the piston 24 under the action of the pressure thereon is sufficient to move the table when the plunger cylinder 18 is opened to the exhaust 23 by the valve 25, but is insufficient to oppose the force of the plunger 19 when the valve is moved so that the plunger is acted on by the pressure fluid in the chamber 28. In other words, the initial movement of the valve 25 to position the enlarged portion 49 thereof either below or above the port 32, will determine whether or not the table is to be moved in one direction by the plunger 19 or in an opposite direction by the piston 24. Further, the lever connection of the piston with the table or movable member 7 provides automatically operable means for displacing the piston to a position corresponding to that which the valve has been set and the pawl 46 insures the parts being maintained in their adjusted positions until the lever 39 is again actuated.

It will be understood that the form of the invention shown and described is illustrative of a preferred embodiment and that such changes may be made as fall within the purview of one skilled in the art, without departing from the spirit of the invention and the scope of the appended claims.

What I claim is:

1. In a machine of the class described, the combination of a movable member, means for adjusting and maintaining the movable member in a predetermined position, said means including a main cylinder and an auxiliary cylinder, means for introducing a pressure medium into the main cylinder, a pressure actuated piston in the main cylinder, a lever mechanism connecting the piston to the movable member to move the latter in one direction, said main cylinder having an exhaust port therein, a pressure actuated plunger in the auxiliary cylinder, said plunger being of larger effective area than the piston, means connecting the plunger to the movable member to move the same in an opposite direction, said piston having a bore provided with a pressure chamber, means for communicating the pressure chamber with the auxiliary cylinder, means for communicating the auxiliary cylinder with the exhaust port, valve means for

selectively controlling the communication of the auxiliary cylinder with the pressure chamber and the exhaust port, means for conducting the pressure medium from the main cylinder to the pressure chamber, and manually operable means for initially setting the valve independently of the movable member to its predetermined position, said piston being acted upon by the pressure medium in the main cylinder at all times so that the force exerted on the piston under the action of the pressure thereon is sufficient to move the movable member when the auxiliary cylinder is open to the exhaust port by the valve but insufficient to oppose the force of said plunger when the valve is moved to establish the flow of the pressure medium from the pressure chamber to the auxiliary cylinder, the connection of said piston with the movable member arranged automatically to displace the piston to a position corresponding to that which the valve has been set.

2. In a machine of the class described, the combination of a movable member, means for effecting relative adjustment of said member, said means including a main cylinder and an auxiliary cylinder, means for introducing a pressure medium into the main cylinder, a pressure actuated piston in the main cylinder, a pressure actuated plunger in the auxiliary cylinder, said plunger being of larger effective area than the piston, means connecting said plunger to the movable member, a lever mechanism connecting said piston to the movable member, said main cylinder having an exhaust port, said piston having a bore provided with a pressure cylinder, the wall of said main cylinder coacting with one side of said piston to provide a passage, means communicating said passage with the auxiliary cylinder, the wall of said piston having axially spaced openings, one of said openings communicating said passage with the pressure chamber, the opposite side of said piston coacting with the adjacent wall of said cylinder to provide a second passage communicating with the exhaust port, the other of said openings communicating the second passage with the bore of said piston, a slide valve extending into the bore of the piston for controlling said spaced openings and operable selectively to control communication of the auxiliary cylinder with the pressure cylinder and the exhaust port, and means for initially setting the valve independently of the movable member to its predetermined position, said piston being acted upon by the pressure medium in the main cylinder at all times so that the force exerted on the piston under

the action of the pressure thereon is sufficient to move the movable member when the auxiliary cylinder is open to the exhaust port by the valve, but insufficient to oppose the force of said plunger when the valve is moved to establish the flow of the pressure medium to the auxiliary cylinder.

3. In a machine of the class described, the combination of a movable member, means for effecting relative adjustment of said member, said means including a main cylinder and an auxiliary cylinder, a pressure actuated piston in the main cylinder, a lever mechanism connecting said piston to the movable member, a pressure actuated plunger in the auxiliary cylinder, said plunger being of larger effective area than the piston, means connecting said plunger to the movable member, said main cylinder having an exhaust port, said piston having a bore provided with a pressure cylinder, the wall of said main cylinder coacting with one side of said piston to provide a passage, means communicating said passage with the auxiliary cylinder, the wall of said piston having axially spaced openings, one of said openings communicating said passage with the pressure chamber, the opposite side of said piston coacting with the adjacent wall of said cylinder to provide a second passage communicating with the exhaust port, the other of said openings communicating the second passage with the bore of said piston, a slide valve extending into the bore of the piston for controlling said spaced openings and operable selectively to control communication of the auxiliary cylinder with the pressure cylinder and the exhaust port, and means for initially setting the valve independently of the movable member to its predetermined position, said piston being acted upon by the pressure medium in the main cylinder at all times so that the force exerted on the piston under the action of the pressure medium thereon is sufficient to actuate the movable member when the auxiliary cylinder is open to the exhaust port by the valve, but insufficient to oppose the force of said plunger when the valve is moved to establish the flow of the pressure medium to the auxiliary cylinder.

KALEB EMIL EVRELL.
